UNITED STATES PATENT OFFICE.

JOHN C. BROOKS, OF PATERSON, NEW JERSEY.

NEEDLE-LOOM.

No. 831,322.

Specification of Letters Patent.

Patented Sept. 18, 1906.

Application filed March 17, 1904. Serial No. 198,667.

To all whom it may concern:

Be it known that I, JOHN C. BROOKS, a citizen of the United States, residing at Paterson, in the county of Passaic and State of New Jersey, have invented certain new and useful Improvements in Looms, of which the following is a specification.

My invention relates to needle-looms; and it has for its principal objects to provide means for preventing each shot of the weft, after being properly placed in position as the fell of the cloth, from being afterward disarranged in the working of the parts of the loom, and to provide means for stopping the loom automatically both on failure of the filling or on failure of the needle to properly project itself through the shed.

In the accompanying drawings, Figure 1 is a plan view of enough of my improved needle-loom to illustrate my invention. Fig. 2 is a vertical sectional view of the loom, showing in side elevation the parts seen in Fig. 1; and Figs. 3 and 4 are sectional views of details.

25 In the drawings, *a* is the breast-beam of the loom, *b*, the batten; *c*, the part at the breast-beam over which the cloth *d* extends on its way to the take-up mechanism, and *e* the knock-off shaft carrying cranks *g*.

30 Suitably supported in fixed position, as by being secured to the breast-beam and to brackets *h*, carried by the frame of the loom, are two elongated cases *i*, arranged parallel with the warp and on both sides thereof.

35 Each of these cases incloses a feeler *j*, having a longitudinal slot *k* and two upwardly-extending lugs *l*, formed in the adaptation shown by bends in the metal of which the feeler is made. These lugs are not directly 40 side by side, but one is a little nearer one end of the feeler than the other. One end of the feeler projects into a hole *m*, which penetrates longitudinally the forward end of the case. The other end is formed with an opening *n*, which receives a lever *o*, fulcrumed in the bracket *h* and pulled against a cam *p* on a rotating shaft *q* by a spring *r*, the lever being adapted to play in a slot *s* in the bottom of the case *i*. There are two of each of the 45 parts *o*, *p*, and *r*, one for each feeler.

50 In each casing is arranged a pin *f*, which projects upwardly through the slot *k* of the

feeler. Each feeler, as it is caused to reciprocate in the casing by the coactive effects of cam *p* and spring *r*, intermittently moves 55 forward slightly beyond the pin *f*. (See Fig. 4.)

t indicates the needle, the same being suitably supported and adapted to move horizontally back and forth through the shed in 60 the usual manner and also through an opening *u* in each case *i*, the weft-thread *v* extending from the supply (not shown) through the needle to the cloth. When the needle has projected itself through the shed as far as it 65 will go, (the dotted-line position, Fig. 1,) an edge-thread carrier *w* is moved vertically to introduce its thread *x* through the loop of the weft-thread formed by the needle. The edge-thread carrier *w* may be of any well-known type and it requires no further description herein. 70

The operation of the parts so far described is as follows: During the time when the bat- 75 ten is back and the shed formed the needle *t* is projected through the latter. While the needle is at or near its limit of movement, (indicated by dotted lines in Fig. 1,) the edge-thread carrier moves vertically to carry its 80 thread through the loop of weft-thread formed by the needle. The needle then re-tracts, and as it does so its loop slips along the portion of the edge thread *x* which stands between the cloth and the edge-thread carrier *w*. Ultimately as the needle 85 recedes it leaves the loop of weft-thread behind it held by the edge thread as the fell of the cloth. During the receding motion of the needle the feelers *j* coact with the pins *f* to successively clasp and firmly hold the 90 edge thread and weft-thread. When the needle passes the left-hand feeler, the corresponding cam *p* permits the spring *r* to actuate lever *o* to advance the feeler, whose lugs *l* pass the pin *f*, and thus form a bend in the 95 edge thread which will hold the latter, and when the needle passes the other feeler the latter will be caused to advance in the same manner, so that its lugs *l* will coact with the corresponding pin *f* to hold the weft-thread *v*. 100 The parts *l* and *f* in each instance therefore not only act to take up any slack in the thread, but isolate the portion thereof between themselves and the cloth from dis-

turbing effects, such as the motion of the needle in receding or with the batten.

In brackets *y* on the breast-beam are fulcrumed bell-crank levers *z*, one end of each of which projects opposite the hole *m* in the corresponding case *i*. The other end carries a link 1 in which is sustained a dog 2, having its free ends notched, as at 3, and pivoted in crank *g*. If the weft (or edge thread) breaks, instead of the feeler being held thereby against movement past the position shown in Fig. 4 it will be forced forward in the case under the pull of its spring *r* until its front end protrudes through the case, actuating-lever *z*, and raising dog 2. Normally the notched end of the dog is below the path of movement of a bunter 4 on the batten, but when it has been raised by lever *z* in the manner just stated it will be struck by the bunter, which will act to rock the knock-off shaft *e* and stop the loom. To the crank *g* is connected by a pitman 5 another dog 6, which is suitably pivoted in the frame.

7 is a detector-lever pivoted in the bunter 4 and having one end projecting in the path of movement of the needle. If the needle properly projects itself through the shed, its tapering end will engage the upper end of the detector-lever and turn the latter on its pivot, raising the other end of said lever, which will cause the latter to stand so as not to engage the dog 6 in the backward movement of the batten; but if the needle should fail to properly work the detector-lever will remain idle and as the batten moves back its lower end will engage dog 6 and cause the same, through the pitman 5, to rock the knock-off shaft and stop the loom.

In order to open out the loop of weft so that the edge-thread carrier may have a clear way therethrough, the upper end of lever 7 may be inclined on the side thereof away from the needle, so that the latter has a tapered point, as at 8. Thus when the lever 7 is engaged by the needle and is moved back by the tapering end thereof wiping against it it will protrude itself up between the needle and thread and, on account of its tapering form, widen the space between them.

Referring again to the means for holding the edge and weft threads, it will be observed that it results in preserving a uniform regular edge on the edge-thread side of the fabric and in the weft-loops being left just as they have been initially beaten up by the reed. There is no undue pull resulting from the subsequent movements of the parts after a given shot of the weft has been placed in position tending to effect indentations in the edge of the fabric, on the one hand, or to pull it away from the fell of the cloth after once being beaten up on the other hand.

Having thus fully described my invention, what I claim as new, and desire to secure by Letters Patent, is—

1. In a loom, the combination of means for carrying the weft through the shed and means, actuating upon said first-named means leaving the shed, for clamping the shot of weft last deposited against the pulling effects of said weft-carrying means, substantially as described.

2. In a loom, the combination of means for carrying the weft through the shed in a succession of loops, means for introducing an edge thread through said loops, successively, and means, actuating after each introduction of the edge thread through a loop of weft-thread, for temporarily securing said edge thread against pulling effects, substantially as described.

3. In a loom, the combination of a weft-introducing needle, a case, said needle being movable through the case, and means, located in the case, for securing the weft-thread upon the retraction of the needle, said means comprising a movable feeler having thread-engaging lugs and a fixed thread-engaging part coactive with said lugs and to hold the thread, substantially as described.

4. In a loom, the combination of means for carrying the weft through the shed in a succession of loops, means for introducing an edge thread through each loop, a case, said weft-carrying means being movable through the case, and means, located in the case, for securing the edge thread upon the retraction of the weft-carrying means, said means comprising a movable feeler having thread-engaging lugs and a fixed thread-engaging part coactive with said lugs to hold the thread, substantially as described.

5. In a loom, the combination of the knock-off shaft, the batten, a bunter on the batten, a crank on the knock-off shaft, a part carried by said crank and normally disposed out of the path of movement of the bunter but movable into the path of movement thereof to be engaged thereby and effect the rocking of the knock-off shaft, means for introducing into the shed the weft-thread in a succession of loops, means for introducing an edge thread through the loops of weft-thread, successively, a moving feeler normally restrained in its movement by one of said threads, and means for transmitting the movement of said feeler to said part upon the breakage of the thread controlling the same whereby to move said part into the path of movement of the bunter, substantially as described.

6. In a loom, the combination of the knock-off shaft, the batten, a crank carried by the knock-off shaft, a pivoted dog, means for connecting said dog and the crank, a weft-carry-

881,322

ing needle, and a detector-lever pivoted on the batten and engageable at one end by the needle, said detector-lever being also engageable with the dog to actuate the same and the 5 knock-off shaft upon failure of the needle to actuate said detector, substantially as described.

In testimony whereof I have signed my name to this specification in the presence of two subscribing witnesses.

JOHN C. BROOKS.
